(57) **CLAIM**

The ornamental design for a watch dial, as shown and described.

DESCRIPTION

FIG. 1 illustrates a perspective view of a watch dial employing an ornamental design in accordance with the present invention;

FIG. 2 illustrates a front view of the watch dial of FIG. 1; FIG. 3 illustrates a left side view of the watch dial of FIG. 1; FIG. 4 illustrates a right side view of the watch dial of FIG. 1; FIG. 5 illustrates a top view of the watch dial of FIG. 1; and, FIG. 6 illustrates a bottom view of the watch dial of FIG. 1. All features illustrated in phantom line are expressly disclaimed and form no part of the claimed design.

1 Claim, 6 Drawing Sheets
